UNITED STATES PATENT OFFICE.

WILLIAM E. SHEEHY, OF NEWFIELDS, NEW HAMPSHIRE, ASSIGNOR OF ONE-HALF
TO LEONARD W. SHEEHY, OF NEWFIELDS, NEW HAMPSHIRE.

POWER HAMMER.

Application filed March 2, 1921. Serial No. 449,022.

To all whom it may concern:

Be it known that I, WILLIAM E. SHEEHY, a citizen of the United States, resident of Newfields, county of Rockingham, State of New Hampshire, have invented an Improvement 5 in Power Hammers, of which the following description, in connection with the accompanying drawing, is a specification, like characters on the drawing representing 10 like parts.

This invention relates to power hammers of the beam or helve type and it has for one of its objects to provide a power helve hammer with novel connection between the 15 crank shaft and the helve which will readily accommodate itself to different thicknesses of work and different lengths of stroke.

Another object of the invention is to provide a helve hammer of this type with an 20 improved form of anvil block and die and otherwise to improve power helve hammers all as will be more fully hereinafter set forth.

In order to give an understanding of my 25 invention I have illustrated in the drawings a selected embodiment thereof, which will now be described after which the novel features will be pointed out in the appended claims.

30 Fig. 1 is a side view of a power hammer embodying my invention.

Fig. 2 is a side view showing the base in 35 longitudinal section and also showing the hammer in its lowered position in contact with the work.

Fig. 3 is an end view of the hammer with the portion thereof shown in section.

Fig. 4 is a top plan view of the die.

Fig. 5 is a section through the anvil block 40 and die on the line 5—5, Fig. 2.

The base or frame on which the hammer is supported is indicated generally at 1 and 2 indicates the helve, which in this type of hammer is usually made of wood, and 3 45 indicates the hammer element secured to the outer end of the helve. The base or frame 1 is provided with the forked stand or support 4, between the arms 5 of which the helve is received and on which said helve 50 is pivotally mounted.

6 indicates the crank shaft by which the helve is operated, said crank shaft being driven by a driving pulley 8 which receives a driving belt 9. The driving belt is made 55 operative to drive the pulley 8 by means

of a belt tightener 10 which is actuated from a foot treadle 11. 7 indicates the anvil block on which the anvil die is supported.

The parts thus far described, with the exception of the frame, are or may be, all 60 as usual in power helve hammers and form no part of my present invention.

I preferably make the frame 1 with the two side members 12 of channel iron and the stand 4 is formed with the portion 13 which 65 fits between the channel members, said stand being bolted to the channel members by suitable bolts 14. At the front end of the frame the channel members are connected by a member 15 which is bolted thereto and to 70 which the anvil block 7 is detachably secured by means of suitable bolts 16. The helve 2 is set into a holder 17, the portion 18 of the helve, which is received in the holder, being tapered and the socket of the 75 holder being correspondingly tapered as best seen in Fig. 2. This holder 17 is provided with recesses 19 to receive hardened centers 20 on which the helve is pivoted, said centers being mounted in the arms 5 80 of the stand 4.

The body portion of each center 20 is square in cross section and each center is supported in a square socket formed in one of the arms 5. Each arm is shown as having 85 the removable cap portion 21 which is bolted to the arm 5 and which clamps the center in position. Each arm 5 is also formed with the flange portion 22 in which is screw-threaded a backing screw 23 by which the 90 center is positioned. A hardened washer 24 will preferably be provided between each screw and the corresponding center. This construction provides for readily adjusting the centers to take up any wear. 95

The connection herein shown between the crank shaft 6 and the helve 2 comprises two links 25 and 26 pivotally connected at 27, the link 26 being pivoted to an ear 28 depending from the helve and the link 25 100 having a yielding pivotal connection with the helve. The crank shaft 6 is connected to the links 25, 26 at their pivotal point 27 by means of a connecting rod 29. The link 25 is pivotally connected at 30 to an eye 105 bolt 31 which is slidably mounted in ears 32 depending from the holder 17, and said eye bolt has a collar 33 thereon and situated between the collar and one of the ears 32 is a rubber buffer 34. The collar 33 of 110

the eye bolt is adjustable thereon by means of a nut 35 screw-threaded to the eye bolt and said collar is normally so adjusted that the links 25, 26 will stand in line with each other as shown in Fig. 1. The relation of the connecting rod 29 to the links 25, 26 is such that the hammer will strike the anvil or the work thereon before the crank passes over its under center, and when the hammer has been brought to rest against the anvil or against the work *w* then further movement of the crank shaft to carry it over the dead center will carry the pivotal point 27 between the links downwardly thus swinging the links out of line with each other and compressing the buffer 34 as shown in Fig. 2. The links 25, 26 and the buffer 34 provide, therefore, a yielding connection between the crank and the helve which permits the hammer to accommodate itself to different thicknesses of work and which gives the hammer the necessary yielding or resilient action to produce a quick snappy blow.

It will be noted that one end of the link structure 25, 26 is connected to the helve through the lug 28 while the other end is connected to the holder 17, and therefore the strain incident to the crank passing around the under center would tend to force the helve backwardly into the holder. The taper construction of helve and holder prevent this action and retain the parts in proper position.

The anvil block 7 supports an anvil die on which the work *w* is received. This die is indicated at 36 and it is carried by a support 37 which is so mounted in a holder 38 that the die can rock into different angular positions. The holder 37 is made with the semi-circular portion 39 which fits a correspondingly shaped recess in the carriage 38, this construction permitting the holder 37 to turn about its semi-circular surface to present the face of the die in different angular positions. One side face 40 of the portion 39 is inclined and the corresponding side face of the recess in which the holder 37 is received is under cut as shown at 41. The holder is retained in the carriage by means of a key 42 which is driven into a slot 43 formed in the carriage and which engages the straight face 44 of the holder.

The key is formed at its small end with a lateral projection 45 which prevents the key from being entirely withdrawn from the slot when it is loosened and I will preferably make the key with a slight curvature longitudinally thereof so that when it is driven home, it will be straightened, thereby producing sufficient friction to retain the key in place. The carriage 38 is provided with a well 50 which has an opening through the

side of the carriage. The function of this well is to catch any dirt which may find its way into the recess in which the holder 37 rocks.

I claim.

1. In a power helve hammer, the combination with a frame carrying an anvil, of a helve member pivoted to the frame and carrying a hammer, two pivotally connected links, one of which is pivoted to the helve and the other of which has a yielding connection therewith, and a crank shaft connected to said links. 70 75

2. In a power helve hammer, the combination with a frame carrying an anvil, of a helve member pivoted to the frame and 80 having a hammer, a crank shaft journaled in the frame, two lugs or ears depending from the helve, two pivotally connected links, one of which is pivoted to one of the ears and the other of which has a yielding connection with the other ear, and a connecting rod connecting the crank shaft to said links. 85

3. In a power helve hammer, the combination with a frame carrying an anvil, of a holder pivoted to the frame, a helve carried by the holder and having a hammer, two pivotally connected links, one of which is pivotally connected to the helve and the other of which is yieldingly connected to 90 95 the holder, a crank shaft and a connecting rod connecting the crank shaft to said links.

4. In a power helve hammer, the combination with a frame carrying an anvil, of a holder pivoted to the frame, a helve member 100 carried by the holder and provided with a hammer, two pivotally connected links, one of which is pivotally connected to the helve, an eye bolt slidably mounted in the holder and to which the other link is pivotally connected, said eye bolt having a collar, a yielding buffer between said collar and holder, and a crank shaft journaled in the frame 105 and connected to the links.

5. In a power hammer, the combination 110 with a hammer member, of an anvil block, a carriage thereon, having a semi-circular seat, one side face of which is under cut, a die holding member having a semi-circular portion to fit said seat, and having one 115 side face inclined to fit the under cut face.

6. In a power hammer, the combination with a hammer member, of an anvil block, a carriage thereon, having a semi-circular seat, one side face of which is under cut, 120 a die holding member having a semi-circular portion to fit said seat, and having one side face inclined to fit the under cut face, and a key for holding the die-holding member in place. 125

In testimony whereof, I have signed my name to this specification.

WILLIAM E. SHEEHY.
